J. W. CORLISS & J. WHARMBY.

PIANO DAMP ABSORBER.

APPLICATION FILED NOV. 18, 1912. RENEWED FEB. 6, 1914.

1,093,979.

Patented Apr. 21, 1914.

UNITED STATES PATENT OFFICE.

JAMES WEBSTER CORLISS AND JAMES WHARMBY, OF LAKELAND, FLORIDA, ASSIGNEES OF ONE-HALF TO JAMES W. CORLISS, OF LAKELAND, FLORIDA, AND ONE-HALF TO CHARLES L. KING, OF ST. PETERSBURG, FLORIDA.

PIANO DAMP-ABSORBER.

1,093,979.

Specification of Letters Patent.

Patented Apr. 21, 1914.

Application filed November 18, 1912, Serial No. 732,115. Renewed February 6, 1914. Serial No. 817,051.

To all whom it may concern:

Be it known that we, JAMES W. CORLISS and JAMES WHARMBY, citizens of the United States, residing at Lakeland, in the county of Polk and State of Florida, have invented certain new and useful Improvements in Piano Damp-Absorbers, of which the following is a specification, reference being had therein to the accompanying drawing.

10 This invention relates to piano damp absorbers, and has for its object the production of an efficient absorber for absorbing dampness in pianos for preventing warping of the different portions of the mechanism and 15 also preventing the sticking of the keys.

Another object of this invention is the production of an efficient casing for a lamp which may be readily disassembled in order to place the lamp therein and remove the 20 lamp therefrom.

With these and other objects in view, the invention consists in general of certain combinations and arrangements of parts as will be hereinafter fully described, illustrated 25 in the accompanying drawings, and specifically claimed.

In the drawings, Figure 1 is a central longitudinal section of the heater. Fig. 2 is a front view thereof. Fig. 3 is a side view of 30 the heater.

By referring to the drawings, it will be seen that 1 designates a base which constitutes a lamp supporter, and this base is provided with a laterally extending rim 2 upon 35 its lower end. A plurality of punched tongues 3 are formed from the side of the base 1, and these tongues 3 support upon their upper ends the lamp 4. A plurality of lugs 5 are supported upon the outer face of 40 the base 1, and these lugs 5 constitute a support for the main heating flue 6. The outer ends of the lugs 5 are bent over as indicated at 7 to constitute an upper rolled edge for the base 1. The heating flue 6 is provided 45 near its lower end with a plurality of ventilating apertures 8, and also an enlarged opening 9 for facilitating the lighting of the lamp and for admitting a large amount of air. Other ventilating apertures 10 are 50 also employed in the heating flue 6.

A pair of laterally extending flue members 11 are carried by the flue 6 and these laterally extending flue members 11 are provided along their upper ends with a plu-

rality of ventilating apertures 12. These 55 flue members support a deflector member 13 which is provided with a plurality of ventilating apertures 14. The deflector member 13, as will be seen by carefully considering Fig. 1, will distribute the heat passing from 60 the laterally extending flue members 11 over a broad surface in view of the fact that the deflector 13 extends from one end of one member 11 to the opposite end of the adjacent member 11. By having the deflector 65 member 13 formed as illustrated, it will be seen that a considerable radiating surface has been produced whereby heat may be radiated from the absorber. This deflector member 13 is formed with a plurality of 70 rolled portions 15, and a second deflector member 16 is supported over the inner ends of the flue member 11 as indicated in Fig. 2. It will be further seen that the deflector 16 will also constitute a wide heat radiating 75 surface for spanning the junction of the laterally extending flue with the vertically extending flue 6. A deflector plate 17 is supported above the lamp 4 and is suspended from the deflector member 16 by means of a 80 bolt 18. In this manner the heat rising from the lamp will strike the deflector plate 17 and be deflected up through the flue 11. A closure plate 19 is carried by each flue 11 and this plate will prevent the heat from escaping 85 from the ends of the flues, but will keep the heat congested so as to have a good effect upon the instrument within which the heater is carried.

From the foregoing description, it will be 90 seen that a very efficient and durable device has been produced which may be formed of sheet metal, and since it may be formed of sheet metal it will be seen that the same may be very cheaply constructed. It will be 95 further understood that owing to the different passages through which the air passes that the same will become very quickly heated to a greater intensity owing to the great amount of circulation which occurs therein. 100

Having thus described the invention, what is claimed as new, is:—

A device of the class described comprising a base provided with inwardly punched supporting tongues, a lug supported on the 105 outer face of said base, a vertically extending flue supported upon said base by means of said lug, laterally extending flues carried

by said vertically extending flue and secured thereto, a deflector member straddling said laterally extending flues, a second deflector arranged over the junction of said laterally extending flues and beneath said first mentioned deflector, each laterally extending flue provided with ventilating apertures formed in the upper face thereof, and a deflector plate suspended over said vertically extending flue from said last mentioned de-

flector for causing heat formed within said vertically extending flue to be radiated to said laterally extending flues.

In testimony whereof we hereunto affix our signatures in presence of two witnesses. 15

JAMES WEBSTER CORLISS.

JAMES WHARMBY.
